UNITED STATES PATENT OFFICE.

ELIZABETH T. HAYWARD, OF ST. LOUIS, MISSOURI.

COMBINATION-UNDERGARMENT.

1,086,364.

Specification of Letters Patent.

Patented Feb. 10, 1914.

Application filed June 28, 1912. Serial No. 705,957.

To all whom it may concern:

Be it known that I, ELIZABETH T. HAYWARD, a citizen of the United States, residing at 535 Clara avenue, St. Louis, Missouri, have invented a certain new and useful Improvement in Combination-Undergarments, of which the following is a full, clear, and exact description, such as will enable others skilled in the art to which it appertains to make and use the same, reference being had to the accompanying drawings, forming part of this specification.

My invention relates to new and useful improvements in combination undergarments, and has special references to a union garment combining in a single article a corset cover, a pair of drawers, and a short skirt member which latter is a part of the drawers.

The principal objects of my invention are to construct a combination undergarment from a comparatively small number of pattern pieces in order to materially reduce the time, labor, and consequent expense of sewing the parts of the garment together and further to materially reduce the waste in cutting the pattern pieces from sections of cloth.

Further objects of my invention are to produce a neat and practical combination undergarment that is applied to the body of the wearer in one operation and which when applied fits smoothly without fullness around the waist or over the hips in order to be particularly adapted for use in connection with tight fitting gowns and dresses.

A particular object of my invention is to form with the drawers portion of the garment, a short skirt like member, which hangs from the rear portion of the waist of the wearer, and which skirt like portion takes the place of a separate short underskirt usually worn over the drawers.

A still further object of my invention is to provide a combination undergarment that can be easily and cheaply manufactured and which can be readily laundried.

With the above and other objects in view, my invention consists in the novel construction, combination and arrangement of parts hereinafter more fully described, claimed and shown in the accompanying drawings, in which:—

Figure 1 is a perspective view of a combination undergarment of my improved construction and showing the front thereof.

Fig. 2 is a perspective view of the garment and showing the rear portion thereof. Fig. 3 is an elevational view showing the garment open. Fig. 4 is a plan view in outline showing the pattern piece of which the drawers are formed. Fig. 5 is a plan view in outline showing one of the duplicate pieces of which the corset cover portion of the garment is formed.

In the embodiment of my invention as illustrated, 1-1 designates the sections of material which, when properly united form the corset cover portion of the garment. These sections are cut from fabric with the warp threads running at right angles to the front edge 2 of each section. Thus, the weft threads lie parallel with the front edge 2. The rear edges 3 of the section 1 are cut on the bias or at an angle relative to the warp and weft thread of the material, and these edges are united in any suitable manner preferably by rows of stitching 4, thereby forming a seam which when the garment is positioned on the wearer occupies a vertical position on the back.

The upper edges 5 and 6 of each section are curved vertically upward toward a common point, and formed in the material below these upperly curved edges is an opening 7 which forms the arm hole of the garment. The edges 5 and 6, which depend from the upper edge of the corset cover together with the edge of the arm hole opening 7 may be trimmed in any desired manner, and attached to the outer upper corners of the sections 1 at the points where the edges 2 and 5 meet are tapes or ribbons 8 which form ties for uniting the upper corners of the corset cover on the front of the wearer.

A narrow strip 2^a of each section 1, immediately adjacent the edge 2, is folded over unto the body of the goods and attached thereto, thus forming a reinforcing or double edge on each end of the corset cover portion of the garment, and formed in one of these reinforcing edges is a series of button holes 9 adapted to receive buttons 10 carried by the opposite edge strip when the front edges of the corset cover are united.

11 designates the pattern piece or section from which the drawers and skirt portion of the garment are formed, which section is cut from a single piece of suitable fabric, 110 and where the fabric is provided with selvage, the same forms the lower edge of the

skirt portion of the garment as designated by 11^a. A semi-elliptic opening or cut-away portion 12 is formed in the center of the upper portion of the section 11 and the 5 edge 12^a of this opening passes around the waist of the wearer, said edge being bound or trimmed as desired and connected directly to the lower edge of the corset cover portion of the garment in any suitable manner.

10 The four corners of the pattern piece or section 11 are cut away so as to form a pair of curved edges 13, and these corresponding edges are united to form the drawers legs and the seams, resulting from joining of 15 these edges extended vertically on the insides of the leg portions of the drawers.

The upper edges 15 of the section 11 between the cut away corners, form the lower edges of the drawers legs, and said edges 20 may be trimmed as desired. The central portion of the section 11 or that portion between the drawers legs, and below the waist opening 12, forms the skirt portion of the garment, and when the garment is in position upon the wearer this skirt portion depends from the rear portion of the waist line of said wearer and folds over the rear portions of the drawers legs. If desired, 25 tapes or ribbons 16 may be attached to the ends of the waist band between the drawers and corset cover in order to form ties for drawing up the waist band when the garment is worn.

By cutting the section 11 so that the selvage of the goods extends along the lower edge of the skirt portion, it will be unnecessary to trim the lower edge of said skirt portion, although the trimming can be added if desired.

40 From the foregoing description, it will be readily seen that I have produced a simple combination undergarment, combining practically three separate garments, namely, drawers, corset cover and short skirt which 45 garment can be easily and cheaply manufactured for the reason that comparatively little time and labor is required in cutting and assembling the three sections of material from which the garment is formed and said garment when worn fits smoothly, presents 50 a neat and finished appearance, and is particularly adapted to be worn with comparatively tight fitting gowns or dresses.

The skirt portion of the garment hangs 55 freely from the rear portion of the waist band and in no wise interferes with the free movements of the wearer. By forming the corset cover sections with the rear or back edges on the bias or at an angle with respect 60 to the warp threads of the goods, all fullness of the corset cover when applied to the

body of the wearer is avoided and a comfortable easily fitting garment is produced.

It will be observed that the garment as a whole, is open at the front from top to bottom, and this construction facilitates the putting on or taking off of the garment, besides permitting the garment to be laid out flat when ironed.

The entire combination garment is formed 70 without darts, and without inserts, and the single seam required to unite the two parts of the corset cover is at the middle of the back of the garment, and but two seams are required in the formation of the drawers, 75 said seams being on the inside of the leg portion of said drawers.

In cutting the section that forms the drawers, the goods from which the section is cut can be folded so as to form two layers, 80 and the pattern from which the drawers are cut is laid on the goods with one edge along the folded edge of said goods, and thus the two layers of the goods are cut at the same time and, therefore, the two halves of the 85 sections are alike in size and shape. If desired, the depending skirt portion may be lengthened by adding a deep flounce along the lower edge of said skirt portion.

Various changes in the form, proportion, 90 and minor details of construction may be resorted to without departing from the spirit of my invention, the scope of which is set forth on the appended claim.

I claim:

In a combination undergarment of the class described, the combination with a waist member, of a pair of drawers formed from a single continuous section of material having a selvage and cut so that said selvage is directly opposite the waist line of the drawers, there being a semi-elliptic opening formed in the center of the edge of the section of material opposite the selvage to form the waist opening, the corners of said section of material being cut away, the edges adjacent to the cut-away portions being connected by seams to form the drawers legs, which seams occupy vertical positions on the insides of the drawers legs of the completed garment, and the material from which the drawers are formed between the legs sections and the waist line depends from said waist line to form a short skirt section.

105 In testimony whereof I hereunto affix my signature in the presence of two witnesses, this 21st day of June, 1912.

ELIZABETH T. HAYWARD
